[57] CLAIM

The ornamental design for a portable television set, as shown and described.

DESCRIPTION

FIG. 1 is a front elevational view of a portable television set showing our new design;

FIG. 2 is a top plan view thereof;

FIG. 3 is a right side elevational view thereof;

FIG. 4 is a left side elevational view;

FIG. 5 is a bottom plan view thereof;

FIG. 6 is a rear elevational view thereof;

FIG. 7 is a top, front and right side perspective view thereof, shown with the antenna in an extended position;

FIG. 8 is a top, front and right side perspective view thereof, shown with the liquid crystal display in a folded position;

FIG. 9 is a front elevational view of a second embodiment of the portable television illustrated in FIG. 1;

FIG. 10 is a top plan view of the embodiment disclosed in FIG. 9;

FIG. 11 is a right side elevational view of the embodiment disclosed in FIG. 9;

FIG. 12 is a left side elevational view of the embodiment disclosed in FIG. 9;

FIG. 13 is a bottom plan view of the embodiment disclosed in FIG. 9;

FIG. 14 is a rear elevational view of the embodiment disclosed in FIG. 9;

FIG. 15 is a top, front and right side perspective view of the embodiment disclosed in FIG. 9, shown with the antenna in an extended position; and

FIG. 16 is a top, front and right side perspective view of the embodiment disclosed in FIG. 9, shown with the liquid crystal display in a folded position.
